UNITED STATES PATENT OFFICE.

HENRY H. LYNCH, OF SAN FRANCISCO, CALIFORNIA.

DREDGER.

SPECIFICATION forming part of Letters Patent No. 365,140, dated June 21, 1887.

Application filed July 26, 1886. Serial No. 209,166. (No model.)

To all whom it may concern:

Be it known that I, HENRY H. LYNCH, of the city and county of San Francisco, State of California, have invented an Improvement in 5 Dredgers; and I hereby declare the following to be a full, clear, and exact description of the same.

My invention relates to certain improvements in apparatus for excavating or dredging; 10 and it consists, mainly, in a novel construction of excavating blades or flanges arranged either spirally or straight, with suitable supporting rings and disks, and a mechanism by which it may be rotated, in connection with a suction-pump, by which the material loosened and excavated by these flanges may be removed 15 as fast as it is excavated.

Referring to the accompanying drawings for a more complete explanation of my invention, Figure 1 is a side elevation of my excavator. Fig. 2 is a longitudinal vertical section. Fig. 3 is an end view. Fig. 4 is a transverse section taken in the plane at right angles with the axis.

In a patent issued to H. B. Angell, May 11, 25 1886, No. 341,539, is shown an excavator composed of a single cylindrical drum having excavating buckets or openings upon its periphery, in combination with a suction-pipe which 30 opens into the drum, and by which the material is removed as fast as it is introduced into the drum by the buckets. I have found that in many classes of work these buckets cannot supply an amount of material sufficient for the 35 suction-pipe, and when this is the case a great quantity of water will be drawn in and a comparatively small amount of solid material. In order to overcome this objection I have discarded the drum entirely, and I employ long 40 curved flanges or diggers A, which are made of boiler-iron or steel riveted or secured together, and supported by strong interior rings, B B, to which they are bolted. In the present case I have shown these digging-flanges attached to the rings, so as to form spirals around the circumference of the structure, and the lower ends are curved inward, as shown more clearly in Fig. 2, and are riveted or bolted to a circular disk, D, which has a strong central 45 hub, and is bored out to receive the lower end of the driving-shaft E. The upper end of the excavator has also a central support or head,

F, through which the driving-shaft passes, and the whole is supported upon an inclined ladder or frame which is hinged to a scow or float, 55 so that the lower end may be raised or depressed to bring the excavator into contact with the earth or material which is to be dug up.

Within the structure formed by the excavating-flanges and supporting-rings is a hood, 60 K', which forms an extension above the suction-pipe, through which the material is drawn as it is excavated. The suction-pipe passes through the upper stationary head or disk, F, before described, and through which the central driving-shaft also passes, and the hood is placed relatively to the position of the excavator when at work, so that its open side will be presented toward the lower side of the excavator. The material which is loosened up 70 by these spiral excavating-flanges falls into the interior upon the top of and around the hood, and the constant suction through the pipe G (which is produced by the pump connected with its upper end, but not shown in 75 the present case) will withdraw its material as fast as it is supplied. The stationary head or disk F, through which the driving-shaft and the suction-pipe pass, is strongly secured to the lower end of the timbers H, which form the 80 ladder upon which the excavator is carried.

I is a man-hole plate covering an opening through the upper end of the excavator, and through which access may be had to its interior whenever necessary.

In connection with these excavating blades or flanges I employ also cutters or diggers J, which are in the form of curved loops or T-shaped plates of steel bolted to the frame-work between the excavating-blades and at suitable 90 points, so as to project slightly beyond the edges of the blades or flanges. These T-shaped cutters serve to loosen up very hard or tenacious material and prepare it to be taken in by the excavating-flanges, and they serve also 95 to protect these flanges from injury by stones or excessively hard material which may be encountered in digging.

The edges of the excavating blades or flanges may be serrated or provided with teeth K, projecting beyond the blades. These teeth are riveted or otherwise secured upon the blades in a substantial manner.

Having thus described my invention, what

I claim as new, and desire to secure by Letters Patent, is—

1. In an excavator, the shaft, the supports for the blades or flanges extending circumferentially about said shaft and at a distance therefrom to form rings, cutting blades or flanges secured at different points on said rings, said blades being arranged spirally on the rings, whereby the material is cut and directed into the interior of the excavator, and a suction-pipe opening into the interior, substantially as described.

2. An excavator composed of the supports for the cutting-blades extending circumferentially about the shaft to form rings, the disks or end plates, and the flanges or blades bolted to said supporting-rings and projecting from the sides and around the lower end, so as to present excavating-edges, substantially as described.

3. An excavator composed of blades or flanges arranged around a central shaft, and an end disk and interior supporting-rings to which these flanges are secured, in combination with a disk or head secured to a supporting ladder or frame, a suction-pipe passing through this disk and an interior hood, and a driving-shaft extending through the upper head and secured to the lower disk of the excavator, whereby the latter may be caused to rotate, substantially as herein described.

4. An excavator composed of the flaring

blades or flanges, an end disk and interior supporting-rings to which the blades are bolted, a shaft extending through and secured to the disk through which power may be applied to rotate the excavator, in combination with a stationary head at the opposite end with flanges, by which it may be secured to a supporting frame or ladder, and a suction-pipe extending through said head and the hood in the interior of the excavator, substantially as herein described.

5. An excavator composed of the flaring or scoop-shaped blades or flanges secured to an end disk, and interior supporting-rings, and having a driving-shaft keyed into the disk, as shown, in combination with T-shaped cutters or loops bolted to the excavator and extending outwardly beyond the edges of the digging-flanges, substantially as herein described.

6. An excavator composed of supporting-rings and straight or spirally-arranged plates supported thereby, projecting from the sides and lower end, and an end disk through which power is applied, as shown, in combination with serrated edges or teeth, substantially as herein described.

In witness whereof I have hereunto set my hand.

HENRY H. LYNCH.
